BUILDING TRIM AND GUTTER STRUCTURE

Robert P. Orr, Kansas City, Mo., assignor to Butler
Manufacturing Company, Kansas City, Mo., a corpo-
ration of Missouri

Filed Mar. 10, 1965, Ser. No. 84,184

Term of patent 14 years

(Cl. D13—1)

FIG. 1 is an end elevational view of an installed building trim and gutter structure embodying my design; the other end view is substantially the same as this end view;

FIG. 2 is a side elevational view of same; the other side view is substantially the same as this side view;

FIG. 3 is an enlarged cross-sectional view taken along line 3—3 of FIG. 1 in the direction of the arrows;

FIG. 4 is an enlarged perspective view of the central portion of the end trim;

FIG. 5 is an enlarged perspective view of a corner; and

FIG. 6 is an enlarged cross-sectional view taken along line 6—6 of FIG. 2 in the direction of the arrows.

The novel features of the design reside in the portions shown in solid lines, the broken lines being for the purpose of illustrating environment.

I claim:

The ornamental design for a building trim and gutter structure, as shown and described.
